UNITED STATES PATENT OFFICE.

JACOB PALEY, OF BROOKLYN, NEW YORK.

HAT-CROWN BLOCK.

Application filed March 5, 1927. Serial No. 173,026.

This invention relates to hat apparatus and has particular reference to a blocking device used for shaping, stretching, or re-blocking hats worn by men or women.

5 Among the objects of the invention is to provide a hat block having relatively movable parts and equipped with heating means for said parts and with simple and efficient manually operated means for actuating said 10 parts and for indicating the extent of the movement thereof and in accordance with standard hat sizes.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a vertical or side elevation 25 with parts in section showing a preferred embodiment of the invention.

Fig. 2 is a plan view with parts in section on the broken line 2—2 of Fig. 1.

Fig. 3 is a fragmentary end elevation with 30 parts in section on the line 3—3 of Fig. 1.

Referring now more specifically to the drawings I show my improved hat block as comprising a base 10 of any suitable size or design, preferably substantially flat, and 35 having mounted upon one end thereof the pedestal portion 11 of the block. Toward the other end of the base is secured a gage plate 12 having graduation marks to indicate at 13 standard hat sizes and at 40 measurements in inches, it being understood that there is a definite correlation between the two means of identifying sizes so that the two scales are in effect but one.

The upper end of the pedestal consists of 45 a cross head 15 having two laterally projecting lugs or bosses 16 having horizontal parallel eyes or guideways 17 in which are fitted and secured a pair of guides in the form of rods 18 extending fore and aft from 50 the cross head and spaced in parallel position to and above the base 10. These guides rods 18 are rigid and are fixed in constant position in the boss 16 by suitable means such as set screws 19.

55 In the center of the cross head midway between the bosses 16 is a bearing 20 in

which is journaled for rotation a compound right and left hand screw 21, the same having a reduced portion 22 into which projects a pin in the form of a screw 23 which 60 serves to hold the screw from endwise movement while it is unlimited as to its rotation in the bearing 20. The shank 24 of the screw extends well forward from the pedestal and is provided with a hand wheel 25 or its 65 equivalent for the rotation of the screw.

The block proper, in its preferred construction, comprises two relatively movable parts 26 and 27 having a hemispherical top and cylindrical bottom or approximately so. 70 These block members are made of any suitable material and preferably hollow so as to accommodate heating elements 28, one in each member.

Each block member is provided with or 75 is mounted upon a cross head comprising a central nut portion 29 and two lug portions 30 spaced equally on opposite sides of the center of the nut portion 29. The lugs 30 are similar in size and form to the lugs 16 80 above described but serve to constitute slideable supports for the block members holding them in definite relation to the guide rods 18 but permitting the block members to slide toward and from each other so that 85 they may abut against each other at their meeting surfaces at the vertical center of the pedestal or to move apart from each other when the practical size of the block is enlarged. The right and left portions of the 90 screw 21 co-operate respectively with the nut portions 29 of the block members and in co-operation with the screw they constitute the means for movement of the block members toward or from each other. For instance, as 95 shown, with the rotation of the hand wheel and shank 24 as indicated by the arrows, the block members are caused to separate, thereby enlarging the practical dimension of the block.

100 One of the members 29 carries a rigidly disposed finger or pointer 31, the point of which is adjusted to co-operate with the scale plate 12 pointing out directly to the operator the size of the hat that is determined by the adjustment of the block members.

105 Each heating unit 28 has a pair of leads 32 extending thereto from insulated wires 33 extending upward from the pedestal 15. All 110 four of the wires 33 are associated with an on and off switch 34 of well known con-

struction so that when the switch is turned on both heating units will be heated simultaneously and to the same degree. It is usual for the block to be heated during most of the operations thereof, although for stretching purposes the block may be used at room temperature.

Each block unit comprises an inner vertical plate 35 of flat form and having a rounded top 36 and having a semi-circular base or bottom 37. Each section of the block also includes a smooth wall or surface portion 26, the upper end of which is in the form of a segment of a sphere and which together with the opposing similar part constitutes a hemisphere when the parts are together. This member also includes a semi-cylindrical skirt or bottom portion which bounds the base 37. For securing these parts together the upper curved portion is provided with a pin 38 which projects downward and through the hole in a lug 39 formed at the top of the plate portion 35, and the parts are finally secured together by any suitable arranged screws 40.

With the foregoing specific description of the mechanism, the mode of operation may be briefly summarized as follows: With the hand wheel and screw rotated as far as it can be toward the right, the two block portions will be brought with their plates 35 in abutting relation, and at this time the indicator 31 will register with the smallest practical size of hat indicated on the plate 12. The switch 34 will be turned on if heat is desired in the block units. The hand

wheel 25 is then turned in the left direction so as to separate the units 26 and 27 as far from each other as will be determined by the amount of tension or stress desired to be placed in the hat which is of course understood to be placed thereover before the block elements are separated. This movement of the screw is continued until the desired size for the hat is indicated by the pointer 31 over the plate 12 and the operation will be then delayed long enough for the proper amount of stretch to become effective especially if the hat has been moistened or steamed for the purpose. 50

I claim:

In a hat crown block, a base, a pedestal extending upward from the base, a cross head carried by the upper end of the pedestal and comprising a central bearing and a pair of bosses spaced on opposite sides thereof, said bosses having parallel horizontal bores, a pair of guide bars fixed in said bores and extending fore and aft from the cross head, a horizontal right and left screw journaled in said cross head bearing, a pair of block portions, and a cross head fixed to each of the block portions, each of the latter mentioned cross heads comprising a central nut portion co-operating with said screw, and a pair of guide lugs slidably mounted upon said bars whereby the block members are caused to move toward or from each other and are held positively from lateral tilting or other movement. 70

In testimony whereof I affix my signature.
JACOB PALEY.
